METAL PROTECTOR FOR FOOTWEAR OR
THE HOOF OF ANIMALSFélix Genecand, Geneva, Switzerland, assignor
to Tricouni Société Anonyme, Geneva, Switzerland, a corporation of SwitzerlandApplication July 27, 1935, Serial No. 33,580
In Switzerland August 2, 1934

10 Claims. (Cl. 168—34)

The present invention concerns a metal protector which can be applied to footwear as well as for shoeing the hoofs of animals. The metal protector is designed to be attached to shoes worn by people but in the case of animals the protector is fixed directly to the animals' hoofs.

The metal protector according to the invention is characterized by a support which fits on to the shoe or hoof to be nailed or shod and enclosed by pieces in the shape of a U showing at least one asperity on the outer side of one of its branches, said asperity having a direction nearly perpendicular to the plane of said branch.

Fig. 1 is a view from below showing two constructional forms of the metal protector according to the invention.

Figs. 2 and 3 are a cross section and a perspective view of a part of one of the constructional forms of Fig. 3.

Fig. 4 is a perspective view of a U-shaped part corresponding to the second constructional form.

Figs. 5 and 6 are perspective views, both of a section of the U-shaped part and also of this part and of its support in the case of a third and a fourth constructional forms.

Fig. 7 is a partial view from below of a fifth constructional form.

Figs. 8 and 9 are views from below and a section of the modified part of a support.

Figs. 10 and 11 show in a front view and a partly side view another modified form of the support.

Finally Figs. 12 to 14 refer to a special way of preparing the U-shaped parts or the support with a view for receiving fixation members.

All the examples given relate to the nailing of shoes.

The metal protector according to the invention does away with one of the customary two supports and the shape of the parts fixed on the support left is, as will be seen, mechanically more resistant.

According to the first of the constructional forms, represented on Fig. 1 and on Figs. 2 and 3, the single support 9 is made of a flat piece of metal of a rectangular section and also bent to fit exactly the shape of the edge of the heel 10, to which it is fixed by a certain number of screws 11.

On the side fixed to the heel and on the outer lateral side the support 9 shows a certain number of notches 12, allowing a free passage, the first to a branch and the second to the corresponding middle part of pieces 13 in the shape of a U.

Held in place by riveting, a dentelated part 14 is fixed outside on the other branch of the U and in such a way that the teeth are pointing nearly perpendicular with respect to the surface of this branch, thus towards the ground when the shoe is being used.

The two branches of the U-shaped part have two holes adapted to register with corresponding holes 15 in the support 9 and in which a U-shaped hook 16 is to be introduced.

The metal protection is placed as follows:

First, the support 9 is screwed on to the heel, then the parts 13 are put in place one by one into the notches 12 and are then fixed by nailing with the hooks 16.

At the place of these hooks, at 17, each part 13 has a small notch allowing the point of a tool to get under the hook, when one of these has to be taken off to change for instance a part 13, the teeth of which have been worn out.

The lower right part of Fig. 1 shows in a second constructional form that it is possible to place the U-shaped parts on the support, not only from the outside as it is the case for the parts 13, but also from the inside according to the arrangement of the piece 18.

This last piece 18 is given in detail by Fig. 4 and differs from the first described pieces in that it consists of one piece of laminated metal cut out and curved in such a way as to make a U, 30 capable to fit the support, and a part turned up perpendicularly on one of the branches of the U and having teeth.

Fig. 5 shows another constructional form of a piece 19 also in metal cut out and curved, but 35 presenting two sets of teeth 20 and 21, made of two parts turned up and placed laterally with respect to one of the branches of the U.

Fig. 6 represents in section a part or piece 22, 40 of the same kind as parts or pieces 13, but differing therefrom in this way that the branch 23 with the teeth 24 is longer than the branch 25 passing under the support 26, this branch being made to be turned down as shown by 27, once 45 the part is placed, which contributes still more towards its perfect fixation.

The support may be made of any metal, but it may be useful to use aluminium. As shown in Fig. 1, it is only placed along the edge of the heel 50 exterior to the shoe and has dentelated parts only along this edge. According to Fig. 7, it is possible to lengthen the two branches of the support towards the inside along the edge separating the heel from the sole, which allows eventually, 55

as shown by this figure, to fix on each branch lengthened 28 a supplementary part 13.

It has already been noticed that the ends of the branches of the support 9 are quickly worn out 5 at 29 (Fig. 1), so that it may be useful to add U-shaped parts as shown in Fig. 7 or to strengthen the support where the wear is the greatest.

It is this last solution which is given in Figs. 8 and 9, showing the ends 30 of a support ending 10 by pads or extra thickness 31.

So as to be able to protect the inside edge of the heel, a support like that of Figs. 10 and 11 can be foreseen where a bridge 32 joins the two ends 33, said bridge having a side 34 finding support against the lateral side 35 of the heel and a side 36 resting on the heel. The side 34 has also points 37 made to penetrate into the sole 38 so as to ensure a good fixation of the whole.

As to the fixing of the U-shaped parts with 20 hooks, also U-shaped, it is possible to avoid piercing the parts by preparing these latter as shown in Fig. 12. Laterally upon the two branches of the U, at 39, notches are provided for the passage of the branches of the U-shaped hook, and 25 the median part of the hook rests in a groove 40 joining the two upper notches.

On the contrary, the piercing of the support can also be avoided by proceeding as indicated 30 on Figs. 13 and 14 that is by making the upper branch 41 of the U-shaped part sufficiently long so that the branches 42 of the hook can be placed outside the profile of the support 43, or, as shown along the notches 44 of the said support. In this 35 case also, the part of the branch 41 which is longer than the support can be turned down, wedging the hook and preventing still better the parts from coming undone.

The two ways given in Fig. 12 and Figs. 13 and 14 could be used together.

40 There are still a good many other ways of fixing the U-shaped parts on to the support, and here following are several examples:

The outer branch of the U-shaped part might be made broader than the branch passing under 45 the support, so that two screws passing through the broader branch and the support could be placed in such a way as to go on either side of the narrower branch without piercing it. These screws could assure at the same time the fixation 50 of the support.

The branch of the U-shaped part passing under the support could be longer than the other or lengthened by one or several teeth. The part or 55 parts longer than the support could be turned down against and over it to hold the U-shaped part in place. This would be approximately a contrary solution to that of Fig. 6, the turned down part being thus long enough to be able to suppress the hook or any other sort of fixation.

60 Laterally to the outer branch of the U-shaped part teeth or tongues cut in this branch by two notches on each side could be foreseen, said teeth or tongues, with a pointed tool, could be pushed into holes or corresponding grooves of the support, so as to assure the immobility of the U-shaped part on the latter.

In the case of a U-shaped part with a broader outer branch, the number of teeth round the 70 edge can be increased or these teeth can be again divided in two groups, between which a notch would allow, in the case where the other branch is turned down over the support, to curve the end of the latter between the two groups of teeth.

75 Finally it is not necessary that the teeth of

the U-shaped parts or pieces be turned only parallel to the edge of the support, as is the case for the parts 13 and 18, or only perpendicularly to that direction, as it is the case for the part 19, because the two directions of teeth could be arranged on one and the same U-shaped part.

I claim:—

1. In a metal protector for foot-wear or the hoofs of animals, the combination of a support and of U-shaped pieces, the median part and one 10 branch of which are lodged in notches provided in the support, said pieces being provided on the outer face of one of their branches with at least one asperity having a direction nearly perpendicular to the plane of said face.

2. In a metal protector for foot-wear or the hoofs of animals, the combination of a support adapted to be fitted to the part to be provided with the metal protector and of U-shaped pieces, the median and one branch of which are lodged 20 in notches provided in the support and so arranged that the U-shaped pieces may be put in place from the outside of the support, said pieces being provided on the outer face of one of their branches with at least one asperity having a direction 25 nearly perpendicular to the plane of said face.

3. In a metal protector for foot-wear or the hoofs of animals, the combination of a support adapted to be fitted to the part to be provided with the metal protector and of U-shaped pieces, the median and one branch of which are lodged in notches provided in the support and so arranged that the U-shaped pieces may be put in place from the inside of the support, said pieces being provided on the outer face of one of their branches with at least one asperity having a direction 35 nearly perpendicular to the plane of said face.

4. In a metal protector for foot-wear or the hoofs of animals, the combination of a U-shaped support which is adapted to be fitted to the part to be provided with the metal protector and the branches of which have at their free ends extensions turned one towards the other, and of U-shaped pieces encircling the support, placed on 40 the latter and the extensions of its branches and provided on the outer faces of one of their branches with at least one asperity having a direction 45 nearly perpendicular to the plane of said face.

5. In a metal protector for foot-wear or the hoofs of animals, the combination of a U-shaped support adapted to be fitted to the part to be provided with the metal protector, the ends of the branches of the support being reinforced, and 55 of U-shaped pieces encircling the support and provided on the outer face of one of their branches with at least one asperity having a direction 55 nearly perpendicular to the plane of said face.

6. In a metal protector for foot-wear or the hoofs of animals, the combination of a U-shaped support adapted to be fixed onto the heel of a shoe and to fit the outer outline of the heel, the two ends of the branches of the support being joined by a bridge extending along the inner edge of the heel and having a part turned down against the corresponding lateral inner face of the heel and ending in parts which are adapted to penetrate 70 into the sole of the shoe, and of U-shaped pieces encircling the support and provided on the outer face of one of their branches with at least one asperity having a direction 75 nearly perpendicular to the plane of said face.

7. In a metal protector for foot-wear or the hoofs of animals, the combination of a support adapted to be fitted to the part to be provided with the metal protector, of U-shaped pieces encircling the support and provided on the outer face of one of their branches with at least one asperity having a direction nearly perpendicular to the plane of said face, each U-shaped piece being provided with two holes going right through their branches perpendicularly to the latter, and the support being also provided at the corresponding places with two holes, and of hooks, which are each placed in a group of four holes, are going in this way through the pieces and the support and are adapted to penetrate thus into the part provided with the metal protector.

8. In a metal protector for foot-wear or the hoofs of animals, the combination of a support adapted to be fitted to the part to be provided with the metal protector and of U-shaped pieces encircling the support, the end of one branch of which being bent out outwards with reference to the body of the branch so as to be nearly per-

pendicular to the plane of the said branch and ending with teeth.

9. In a metal protector for foot-wear or the hoofs of animals, the combination of a support adapted to be fitted to the part to be provided with the metal protector and of U-shaped pieces encircling the support and one branch of which is laterally provided on each side with a set of teeth bent out outwards with respect to the U so as to be nearly perpendicular to the plane of the branch.

10. In a metal protector for foot-wear or the hoofs of animals, the combination of a support adapted to be fitted to the part to be provided with the metal protector and of U-shaped pieces encircling the support and provided on the outer face of one of their branches with at least one asperity having a direction nearly perpendicular to the plane of said face, one branch of the U-shaped pieces being longer than the width of the part of the support to which it is applied and being bent over said part.

FÉLIX GENECAND.
